SHEET BINDER

George G. Grinnell, Portland, Oreg.

Application January 3, 1941, Serial No. 373,021

14 Claims.

(Cl. 1—40)

My invention relates to sheet binders.

One of the objects of my invention is to provide improved apparatus for forming binder elements from wire, drilling a pad of sheets to be bound, and inserting the binders through the drilled holes in the sheets.

A further object of my invention is to provide improved apparatus for feeding a pad of sheets laterally step by step, perforating the pad, and inserting binders or fastener elements through the perforations.

A further object of my invention is to provide apparatus for drilling superimposed sheets without burring the outermost sheets.

A further object of my invention is to provide an improved apparatus for forming binder elements from flat wire.

A further object is to provide an improved multiple loop binder formed of flat wire.

Further objects and advantages of the invention will be apparent from the description and claims.

In the drawings, in which my invention is illustrated,

Figure 1 is a perspective view showing the fastener forming element apparatus;

Fig. 2 is a perspective view showing the drilling and inserting apparatus;

Fig. 3 is a plan view of the fastener forming mechanism;

Fig. 4 is a perspective end elevational view of the fastener forming apparatus;

Fig. 5 is a perspective view showing the wire feeding apparatus, the wire severing apparatus, and the tool and die forming apparatus;

Fig. 6 is a longitudinal vertical sectional view showing the tool and die forming apparatus;

Fig. 7 is a horizontal section on the line 7—7 of Fig. 6;

Fig. 8 is a vertical transverse section on the line 8—8 of Fig. 7;

Fig. 8a is a perspective view showing the tool and forming die;

Fig. 9 is a perspective view of one of the fastener elements;

Fig. 10 is a front elevational perspective view of the drilling and inserting apparatus;

Fig. 11 is a perspective view showing the tape feeding and fastener segregating mechanism;

Fig. 12 is a perspective view showing the segregating mechanism and inserting mechanism;

Fig. 13 is a vertical transverse section showing the segregating mechanism, inserting mechanism, and the drilling mechanism;

Fig. 14 is a vertical section showing the drilling mechanism;

Fig. 15 is a horizontal section on the line 15—15 of Fig. 14;

Fig. 16 is an enlarged transverse vertical section showing the inserter, forming anvil, and forming die;

Fig. 16a is a transverse vertical section similar to Fig. 16 but showing the parts in a different position;

Fig. 17 is a horizontal sectional view on the line 17—17 of Fig. 13;

Fig. 18 is a bottom view of the tablet carriage;

Fig. 19 is a perspective view showing a multiple coil fastener; and

Fig. 20 shows the elongated fastener of Fig. 19 before it is inserted.

Referring to the drawings in detail, the construction shown comprises a mechanism for withdrawing flat wire 1 from a reel, straightening it, and feeding it to a forming device 2 (Figs. 6, 7, and 8), mechanism 3 for cutting the wire into sections of the proper length for forming the U-shaped fasteners 4, mechanism including a plunger 5 and die 6 for forming the severed sections into U-shaped fastener devices 4, guide means 7 (Figs. 1 and 2) for delivering the U-shaped fasteners 4 from the forming device to a segregating and feeding mechanism 7a, means 8 for drilling holes in a tablet 11 with the holes suitably spaced to receive the ends of the U-shaped fastener 4, and means 10 for removing the fasteners, one at a time, from said segregating device, inserting them through the holes in the tablet 11, and forming them into a twin loop binder 12 (Figs. 2, 11, 12, 13, 14, 15, and 16).

The mechanism for withdrawing the wire from the reel and feeding it to the forming die comprises a pair of friction feed wheels 13 (Figs. 3, 4, and 5) constantly driven from the motor 14, for frictionally feeding the wire 1 to the forming device 2, a pair of friction feed rolls 15 for insuring a sufficient supply of wire to the feed rolls 13, also constantly driven from the motor 14, and guiding and straightening rolls 16 for straightening the wire as it is removed from the reel and guiding it to the feed rolls 15.

In order to adjust the speed of the feed rolls 13 and 15 to insure the proper rate of supply, a variable speed drive is provided between the motor 14 and feed rolls comprising a friction disc 17 (Figs. 3, 4, and 5) mounted on the shaft 18 of the feed rolls 13 and 15 and a friction wheel 19 shiftable across the face of this friction disc 17 and splined to a shaft 20 on which the gear 21 is

mounted. This gear 21 is driven from the motor 14 by means of a pulley 22 on the motor shaft 23, a belt 24 running over this pulley, and a pulley 25 over which this belt 24 runs mounted on a shaft 26 on which the pinion 27 is mounted which meshes with the gear 21. Any suitable means may be provided for controlling the speed of the motor 14.

The means 3 for severing the wire into sections of the proper length comprises a shearing knife 28 underneath the wire 1 as it travels, as shown in Figs. 6 and 8, and an L-shaped arm 29, on which this knife is mounted, pivotally mounted at 30 (Figs. 1, 3, 4, and 5). A spring 31 is provided which normally holds the knife 28 in lowered position. An electromagnet 32 is provided cooperating with an armature 33 on the knife arm to effect the severing action of the knife. This electromagnet 32 is energized in timed relation with the staple-forming tool 5 by means of a U-shaped circuit-closing conductor 34 (Figs. 3 and 5), mounted on the same motor-driven shaft 20 on which the motor-driven gear 21 is mounted. Each revolution of this shaft will close the circuit for the electromagnet through the contacts 35 and 36 and the U-shaped conductor 34.

The mechanism for forming the U-shaped fastener comprises the die element 6 having opposed guides or grooves 36a (Fig. 8a) for receiving and forming the arms of the U-shaped fastener, and a plunger tool 5 slidable in a guideway 36b cooperating with this die 6, operating transversely of the direction of travel of the wire 1 and serving to force the severed section of wire into the die to cause the section to assume the U-shape as shown in Figs. 6, 7, 8, and 9.

The plunger tool 5 is operated from the same motor-driven shaft 20 which feeds the wire 1 and controls the movement of the knife 28, by means of a crank 37 mounted on the motor-driven shaft 20, a connecting rod 38 pivotally secured at 39 to the crank 37, and a wrist pin connection 40 with the slide 41 to which the fastener-forming tool 5 is secured. With this construction, it will be seen that each revolution of the motor-driven shaft 20 will cause a section of wire to be cut off by the knife 28 and will cause the tool 5 to make one complete stroke back and forth to form one of the U-shaped fasteners. At the same time the friction feed wheels 13 will be rotated to cause the wire to be advanced sufficiently to provide material for another fastener. An adjustable stop 42 (Figs. 5 and 7) is interposed in the path of travel of the wire to stop the travel for an instant while the wire is being severed. The instant the section is severed off, the plunger tool 5 engages the middle part of the section and forces it into the die. Means are provided for enabling the feeding of the wire to be resumed while the plunger die is making this stroke back and forth. For this purpose, the edge of the plunger is beveled, as shown at 43 (Fig. 8), to enable the advance end of the severed wire to ride up along this incline 43 and to pass across and above the plunger as the plunger is making its back-and-forth stroke, as shown in Fig. 8.

In order that the plunger may engage the wire when the plunger begins its advance, the front end of the plunger is relieved to provide a fastener-engaging shoulder 44 (Figs. 6, 7, and 8a). In order to insure that the wire is brought down so as to be in the path of this shoulder 44 when the plunger 5 begins its advance, a cam-controlled, spring-pressed depressor slide 45 is provided. This depressor slide 45 is mounted in fixed

guides 46 adjacent the entrance to the die and is urged downwardly by means of a compression spring 47. The downward movement of this depressor slide is controlled by a cam depression 48 in a cam bar 49 which reciprocates with the plunger tool 5, as shown in Figs. 5 and 6. When the plunger tool 5 is withdrawn so that the relieved front portion 50 (Fig. 8a) of the plunger is underneath the wire 1, the cam depression 48 will have been moved to a position which will enable the wire depressor 45 to move downwardly to force the wire 1 onto the relieved portion 50 of the plunger tool. This insures that the flat wire will not buckle up and elude the front edge of the shoulder portion 44 of the forming tool in its initial movement.

In order to straighten out the connecting portion 51 of the U-shaped fastener, a reciprocable cam-controlled, spring-pressed stop 52 is provided (Figs. 6 and 7). This stop 52 is moved up and out of the way by the cam bar 49 to enable the ejection of the completed fasteners and is moved down into the path of the connecting part 51 of a succeeding fastener by means of a compression spring 53 when the depressed cam portion 48 of the cam slide comes underneath the follower portion 54 of the reciprocable stop.

In order to insure that the fastener 4 is not withdrawn or partially withdrawn as the plunger tool 5 returns, a snap spring detent 55 is provided, secured at one end at 56 and having its free end 57 in position to snap down into the recess 58 in the shoulder 44 of the tool 5 behind the crosspiece 51 of the U-shaped fastener when this crosspiece is pressed against the reciprocable stop 52. The die 6 and tool 5 are relieved and rounded off where necessary to facilitate the bending and forming operations.

The means for delivering the fasteners from the forming device 2 to the selecting and segregating plunger 59 (Figs. 13 and 17) comprises the guide rail 7 which the U-shaped fasteners 4 straddle as they are pushed out of the die by the plunger tool 5 and down which they gravitate to form a vertical stack 60 of substantially horizontal fasteners above the segregating plunger 59. A guard rail 61 is provided above the guide rail to insure that the fasteners remain in engagement with the guide rail 7.

The tablet drilling and fastener-inserting mechanism comprises broadly a horizontally movable carriage 62 (Figs. 2, 10, 13, 16, and 18) on which the pad of sheets 11 to be fastened together are secured in position, a treadle-controlled step-by-step feed for this carriage to shift the tablet edgewise after each drilling and fastener-inserting operation to bring the tablet in position for another drilling and fastener-inserting operation, a treadle-controlled return mechanism for returning the tablet carriage to initial position after all of the fasteners have been inserted, a pair of rotary drills 63 (Figs. 2, 12, 14 and 16) for drilling a pair of holes in the tablet pad, properly spaced to receive the legs 64 of a fastener element and a mechanism 10 for aligning the fasteners and inserting them "feet first" through the pair of previously-drilled holes in the tablet pad 11.

Three motors are provided, one 64 (Fig. 10) for effecting the rotary movement of the pair of drills 63, another 65 for effecting the return travel of the tablet carriage 62 and another 66 (Fig. 11) for effecting the other operations including the axial feed movement of the drills 63, the escapement mechanism for the step-by-

step feed of the tablet carriage, the insertion of the U-shaped fastener element, and the feed for the two guard tapes 67 and 68 which are fed, respectively, above and below the tablet 11 as it is being drilled, to prevent the mutilation of the outside sheets of the tablet by the point of the drill. The operation of the pedal 69 (Fig. 10) causes the axial movement of the drill head 8, the actuation of the pedal 70 causes the insertion of a fastener element, and the operation of the pedal 71 causes the return of the tablet carriage.

In operation it is customary, first, to depress the pedal 69 to drill a pair of holes in the tablet pad 11 without causing the operation of the fastener inserter, then to shift the foot slightly to the left, as viewed in Fig. 10, so as to rest on both pedals 69 and 70, and depress both pedals to cause the insertion of a fastener 4 into the two holes and to cause the drilling of two holes spaced from the first two holes for the subsequent insertion of another fastener. As explained hereinafter, each time the pedal 69 is depressed, it will cause an up-and-down movement of the drills 63 and a one-step feeding movement of the carriage 62.

For the insertion of the final fastener element of the tablet sheets, the operator may either depress both pedals 69 and 70, causing the rise of the drill head and the insertion of a fastener in the last pair of holes in the tablet (the tablet having passed beyond the position in which it will be in the path of the drills), or the operator may simply depress the inserter pedal 70 causing the insertion of a fastener without any axial movement of the drill head. When the last fastener has been inserted in the tablet, the operator depresses the carriage-return pedal, causing the carriage to return to its initial position.

After passing through the tablet, the point of the drill enters a wooden block 72 (Fig. 13) which is automatically pressed against the upper guard tape during the drilling operation. The first drilling movement forms a guide recess or pocket in the under face of the wooden block 72 which serves to center the point of the drill as it passes through the tablet.

The mechanism for feeding the U-shaped fasteners from the vertical stack 60 to the forming anvil 73 and forming die 74 (Figs. 12, 13, 16, and 17) comprises the selecting and segregating plunger 59 operating in a horizontal plane underneath the stack of fasteners, and a pair of spaced parallel aligning rock arms 75 (Fig. 13) for moving the segregated fastener 4 from a horizontal position to a vertical position in alignment with the inserter plunger 76 which reciprocates up and down and, on its downward stroke, engages the cross bar 51 of the U-shaped fastener 4 and forces the fastener downwardly to cause its lower ends to bend around inside of the arcuate guide channels in the die 74 and around the semicylindrical surface of the anvil 73, as shown in Figs. 10, 12, 13, and 16.

A suitable spring-pressed presser foot 76a is provided for holding the tablet pad 11 down on the carriage 62 during the inserting operation.

The drive for the step-by-step carriage feed comprises a cord or cable 77 (Fig. 10) having one end 78 secured to the tablet carriage 62 and the other end 78a secured to the frame, a pulley 79 over which this cable 77 passes, and a weight 80 to the upper end of which a pulley 81 is secured, about which the cable passes. The step-

by-step release or escapement for the carriage travel (Figs. 2, 10, and 13) comprises a reciprocating stop slide 82, the upper end 83 of which cooperates with stop pins 84 inserted in spaced openings 85 on the rack bar 92 secured to the carriage, a lever 87 pivotally mounted at 88 (Figs. 2 and 11) and having one end pivotally secured at 89 to the stop slide 82, and a cam 90 mounted on a clutch-controlled motor-driven shaft 91 (Figs. 11). Each time the shaft 91 makes one revolution, the cam 90 will cause the lever 87 to rock up and down and will cause the withdrawal and return of the stop pin 83 on the slide 82 with respect to the stop pins 84 on the carriage rack 92. The movement of this stop slide 82 is so rapid that it will release one stop pin 84 on the carriage and catch the next stop on the carriage before the weight 80 has time enough to pull the carriage stop past the stop slide 82.

For returning the carriage to initial position after it has completed its step-by-step feeding movement to the left, as viewed in Fig. 10, an endless cable 93 is provided having a lost-motion connection with the tablet carriage 62 and passing over the end pulleys 94 and 95. The cable 93 may be brought into driven relationship with respect to the drive pulley 96 by means of cable tightener pulleys 97 and 98 mounted on the pedal-controlled rock lever 99. The drive pulley 96 is driven from the motor 65 by means of a cable 100 passing over the drive pulley 101 on the motor and over a driven pulley 102 mounted on the shaft 103 to which the drive pulley 96 is secured.

When the carriage return pedal is depressed, it pulls the carriage stop 83 out of the way of the stop abutment 84 of the carriage and rocks the rock lever 99 about its pivot 104 to move the cable tightener pulleys 97 and 98 upwardly to press the cable 93 firmly against the drive pulley 96. The carriage return pedal 71 is secured to the stop slide 82 by means of a link 105, a crosshead 106 (Fig. 2) secured to the link 105, and a coil compression spring 107 engaged by the crosshead 106 and bearing on the head 108 of a slide rod 109 secured to the slide 82. The cross head 106 slides on the rod 109 until the spring 107 is compressed sufficiently to press the slide 82 downward. The rock lever 99 is secured to the crosshead 106 by means of a rod 110 pivotally connected with the lever 99 at 111. A spring 112 is provided which tends to hold the stop slide 82 in raised position and to hold the cable tightener pulleys 97 and 98 away from the cable 93.

The cam 90 can cause withdrawal and return of the stop 83 without causing movement of the cable tightening lever 99, since the rod 109 is slideable in the crosshead 106. When the pedal 71 is depressed it first actuates the cable tightening lever 99 and then, when the downward pressure of the spring 107 overcomes the upward pressure of the spring 112 on the stop slide 82, the stop 83 will be withdrawn to enable the drive pulley 96 to return the tablet carriage 62 to starting position.

The right-hand movement of the carriage 62, as viewed in Figs. 2 and 10, under the driving action of the drive pulley 96, is limited by means of a button 113 on the carriage-return cable which engages a stop 114 on the frame. A connection is provided between the carriage return cable 93 and the tablet carriage by means of a button 115 secured to the cable and engaging a forked abutment 116 on the carriage, which straddles the cable so that the button 115 on the

cable can engage the fork. Because of the forked connection 116 between the cable and carriage, the carriage may be readily disconnected and removed from the cable when desired.

In order to insure that the first set of feed rolls 15 will supply wire to the second set of feed rolls 13 as fast as necessary and in order to prevent an oversupply of wire to the second set of feed rolls, means are provided for separating the first set of feed rolls 15 to stop the wire feeding operation when the loop 117 of wire between the first set of rolls and the second set of rolls exceeds a certain length and to bring the first set of feed rolls 15 together again to resume the feeding operation when the length of this loop decreases beyond a certain extent. The means shown may comprise an electromagnet 118 energized when the loop 117 exceeds a certain length and deenergized when the loop falls below a certain length, and transmission between the armature 119 of this electromagnet and the first set of feed rolls to separate the rolls when the electromagnet is energized and to bring them together again when the electromagnet is deenergized.

For controlling the electromagnet a switch is provided having a switch arm 120 (Fig. 4) located in the range of movement of the upper strand of the loop 117, the strands of the loop being guided and held against lateral movement by a wire guide lock 121. If the first set of rolls 15 feeds the wire so fast that the loop 117 increases in size to such an extent as to engage and move the switch arm 120, the electromagnet 118 will be energized, causing the feed rolls 15 to separate and stop feeding the wire. This causes the loop 117 to decrease in size as the rolls 13 continue to feed. As the loop 117 decreases in size it disengages the switch arm 120, which drops to open position to deenergize the electromagnet 118, causing the rolls 15 to resume their feeding operation.

The mechanism for withdrawing the tapes 67 and 68 from the storage spools 122, guiding them to positions, respectively, above and below the tablet being bound (Figs. 2, 10, 11, 12, and 14) comprises the guides 123 for directing the tapes into position with respect to the tablet, and a pair of step-by-step feed rolls 124 between which both tapes pass after they have moved past the tablet. The mechanism for giving the step-by-step feed to these two feed rolls comprises a ratchet wheel 125 (Figs. 2 and 11) on the shaft of one of the feed rolls 124, a rock lever 126 coaxial with this ratchet wheel, a pawl 127 mounted on this lever actuating the ratchet wheel 125, a link 128 pivotally connected with the rock lever, a bell crank pivotally mounted at 129 and having one arm 130 pivotally connected with the link 128, a connecting rod 131 pivotally connected at 132 with the other arm 133 of the bell crank, and a crank 134 (Fig. 10) to which the other end of the connecting rod is pivotally secured, mounted on the shaft 91. With this construction, it will be seen that every time the shaft 91 is given a single revolution the pawl carrying lever 126 will be given a movement back and forth to effect a single feed step of the tape feed rolls 124. The transmission is so timed that the step feed of the tape will be made at a time when the drills 63 are withdrawn from the tablet so as not to interfere with the tape feeding movement.

As previously indicated, the purpose of the guard tapes 67 and 68 is to prevent the mutilation of the outside sheets of the tablet by the point of the drill. The feed for these tapes is com-

paratively slow. After passing through the feed rolls 124, the perforated tapes pass downwardly and may be torn off by the operator from time to time and thrown away or otherwise disposed of.

The drive for the shaft 91 is from the motor 66 through the belt 135 (Figs. 10, 11, and 12) running over the pulley on the motor shaft, a pulley 136 over which the belt runs, a shaft 137 on which this pulley is mounted, a sprocket wheel 138 mounted on this shaft, a sprocket chain 139 running over this sprocket wheel 138 and a large sprocket wheel 140 connectible and disconnectible with respect to the shaft 91 by means of a clutch 141 (Fig. 11) controlled by the pedal 69 in such a manner that when the clutch is released the shaft 91 will stop in a fixed definite position.

The transmission from the clutch pedal 69 (Fig. 10) to the clutch 141 comprises a rock arm 142 mounted on the rock shaft 143 to which the pedal 69 is secured, a link 144 pivotally connected at one end to this rock arm, and a clutch controlling member 145 pivotally secured to the upper end of this link. This clutch pedal 69 which controls the tape feeding operation also controls the axial movement of the drills 63 in effecting the drilling operation. The transmission, by which this axial feed movement of the drill head is effected, comprises a bevel gear 146 mounted on the shaft 91, a bevel gear 147 (Figs. 2, 11, 14 and 15) meshing with the first bevel gear 146, a shaft 148 on which this second bevel gear 147 is mounted, a combination cam and crank disc 149 secured to this shaft 148, and a connecting rod 150 pivotally secured to the crank shaft at one end and pivotally secured to the vertically slideable drill head 151 at the other end. With this construction it will be seen that every time the tape is given a feed step the drill head 151 is caused to be moved up and down in proper timed relation.

From the preceding description, it will be seen that each time the pedal 69 is depressed the shaft 91 will be given one complete revolution, which causes the up-and-down movement of the drill head 151, the one-step feeding movement of the tape, and the one-step feeding movement of the tablet carriage 62, all in proper timed relation.

In order to bring the wooden block 72 down on the tablet at the proper time in the drilling operation, it is mounted on a slide 152 vertically movable in the standard 153 and caused to move up and down by means of the cam formed on the edge of the crank disc 149 which engages a follower roller 154 on the lever 155 pivotally mounted at 156 and connected with the vertically movable slide 152 by means of a connecting rod 157 pivotally secured to the lever at 158 and pivotally secured to the sliding block at 159.

The mechanism for driving the segregator slide comprises a connecting rod 160 pivotally secured at 161 (Figs. 11, 12 and 17) to the segregator slide 59, a lever 162 to which the other end of this connecting rod is secured, pivotally mounted at 163, a roller 164 on this lever, a rotatable cam 165 engaging this roller to actuate the lever 162, a clutch 166 for connecting and disconnecting the rotatable cam 165 with respect to the gear 167, and a pinion 168 (Fig. 11) meshing with this gear 167 and mounted on the motor driven shaft 137. The clutch 166 is controlled from the pedal 70 so that when the pedal 70 is depressed it will cause the clutch to be connected to cause the cam 165 to rotate. The clutch 166 is so designed that when the pedal 70 is

raised, the clutch will be disconnected and the cam will stop in a fixed definite position in which the segregator slide 59 will be in its withdrawn position.

The transmission from the pedal 10 to the clutch 166 comprises the rock shaft 169, to which the pedal is secured, a rock arm 170 secured to this rock shaft, and a connecting rod 171 pivotally connected with this rock arm and extending to the clutch to control its operation. When the clutch 166 is actuated to cause rotation of the cam 165, the lever 162 is moved back and forth to cause the segregator slide 59 to select the lowermost fastener from the stack 60 and feed it horizontally under the rock arms 75.

The mechanism for controlling the operation of the two rock arms 75 which move the fastener element away from the segregator slide 59 into vertical position in the path of the inserter plunger 76 comprises a rock shaft 172 (Figs. 13 and 17) on which the rock arms 75 are mounted, a latch member 173 (Fig. 12) having a latch shoulder 173a secured to the end of this rock shaft, a rocking detent 174 pivotally mounted at 175, the upper end of which is engageable and disengageable with respect to the latch member 173, and a trigger rod 176 engaging at one end the lower end of the detent member 174 and engageable at its other end by an adjustable screw 177 threaded in a bracket 178 secured to the segregator slide 59. A coil tension spring 179 is provided which will effect the swinging movement of the latch 173 (counterclockwise), rock shaft 172, and rock arms 75 when the detent 174 is moved to disengage the latch member 173 which is provided with a shoulder 173a into which the upper end of detent 174 normally is engaged, as shown in Fig. 12. For returning this latch member 173 at the end of the down stroke of the inserter plunger 76, a cam member 180 is provided, movable up and down with the inserter plunger 76 and engageable with the latch member 173 at the lower end of its movement to move the latch member in a clockwise direction to restore its latched position with respect to the upper arm of detent 174 in the shoulder 173a.

The drive for the vertically reciprocable inserter plunger 76 comprises a crank 181 rotatable with the motor driven cam 165, a connecting rod 182 pivotally secured at 183 to this crank, and a wrist pin 184 pivotally connecting the plunger end of the connecting rod 182 to the inserter slide 76. As the inserter slide moves downwardly, the cross bar 51 of the U-shaped fastener 4 is engaged between the sloping face 185 (Figs. 16 and 16a) of the slide and the oppositely sloping face 186 of a spring-pressed plunger 187 slidably mounted in a guide bore in the plunger 76. As the plunger 76 moves downwardly, the fastener is forced downwardly ahead of the plunger, the legs of the fastener entering the arcuate channels in the die 74. This die causes the legs to curl into an arcuate shape, as shown in Fig. 16, and steers the ends of the legs into the drilled openings in the tablet 11. The semicylindrical anvil 73 cooperates with the die in directing the legs in this curling movement. At the time when the free ends of the curled legs have formed a trifle more than a complete circle, as shown in Figs. 16, the spring-pressed plunger will have engaged the stop finger 188 on the adjustable stop 189 to limit the movement of the spring-pressed plunger, thus freeing the crossbar of the U-shaped fastener from engagement between the oppositely sloping faces 185 and 186. Further

movement of the slide 76 will cause the beveled end 185 of this slide 76 to engage the crossbar of the fastener and force this crossbar 51 and the upper ends of the legs of the fastener into the position shown in Fig. 16, the U-shaped fastener then being shaped substantially as shown in Fig. 19. Since the crank 181 is on the same clutch-controlled shaft as the segregator-controlling cam 165, the segregator slide 59, aligning arms 15, and the inserter plunger 76 will be operated in proper timed relation.

In order to enable the tablet carriage to be shifted laterally after the fastener is inserted, the die 74 (Fig. 13) is mounted so that it can be moved out of the way of the tablet to enable this feeding operation. For this purpose the die is pivotally mounted at 190 and is controlled by a cam 191 (Figs. 12 and 13) mounted on a rock arm 192 pivotally mounted at 193 and a plunger rod 194 slidably mounted in the bracket 195, pivotally connected with the rock lever 192 and carrying a follower roller 196 at its upper end for cooperation with a cam 197 rotatable with the cam 165. A coil tension spring 198 is provided for insuring that the die 74 will swing downwardly when the cam 191 is moved downwardly to move the cam surface 199 out of the way of the pivoted die 74. Thus the pivoted die 74 is moved in proper timed relation with respect to the operation of the inserter slide 76 to enable the die to swing clear of the tablet in its lateral feeding movement.

Referring to Figs. 12, 13, and 16, when the die 74 is in its lowered position, its curved forming surface will be moved away out of contact with the inserted fastener so that when the tablet is shifted laterally the loop of the fastener can readily slip laterally off from the anvil 73 without any drag from the forming die 74.

The presser foot 76a is mounted on a slide rod 200 (Figs. 2, 10, 12, and 13) which is slidable in a bracket 201 secured to the standard 153 in which the vertically reciprocable plunger 76 is mounted. The upper end of the slide rod 200 is connected to the standard by means of a coil tension spring 202. The downward movement of the presser foot it effected by the engagement of the lower edge of the guide sleeve 203 carried by the plunger 76 with a washer 203a surrounding the slide rod 200 and bearing on a coil compression spring 204 which at its lower end bears on a shoulder 205 on the slide rod. As the plunger 76 carrying slide 76 moves downwardly, the sleeve 203 engages the washer 203a which bears on the compression spring 204, compressing this spring until sufficient downward pressure is exerted on the slide rod 200 to overcome the action of the coil tension spring 202. This will cause the presser foot 76a to engage the upper face of the tablet to hold it in proper position while the fastener is being inserted.

The tablet is held in place on the carriage by means of suitable adjustable flanges 206 and 207 (Figs. 2, 10 and 13) engaging the side edges of the tablet pad. The right-hand positioning flange (as viewed in Fig. 10) is laterally adjustable on the carriage by means of screws 208 extending through the face of the flange and threaded into any one of a plurality of pairs of openings 209 in the carriage (Figs. 10 and 18). Means are provided for quickly effecting a withdrawing clamping action of the left-hand flange 207 in placing the tablet pad in position and in removing it. For this purpose, the left-hand flange is slidably mounted in a bracket 210 secured to the carriage 62 and is pressed toward the opposing

flange by means of a pair of coil compression springs 211. For withdrawing this flange from engagement with the edge of the pad, a depressible hand lever 212 is provided mounted on the bracket 210 in such a manner that depressing this hand lever will withdraw the flange 207 against the action of the coil compression springs 211. The bracket which carries this spring-pressed flange is adjustably secured to the carriage by means of screws extending through the bracket and threaded into any pair of the adjustment holes 209 in the carriage.

The distance to which the tablet pad may be pushed inwardly is limited by means of adjustable stops 213 (Figs. 2, 10 and 12) on the frame of the machine.

The carriage is provided with four rollers 214 which travel on parallel tracks 215 provided by the flanges of a channel member 216 secured to the frame (Figs. 13 and 18).

In use, when the machine is supplied with the material to be operated on, including the flat wire 1 and the guard tapes 67 and 68, and the machine is put in operation, the fastener forming mechanism operates continuously as previously described to supply the U-shaped fasteners 4 to the guide 7 from which guide they are removed, one at a time, by the segregating and feeding mechanism 7a. The timing of these successive operations of the feeding mechanism is controlled by the operator. As previously indicated, the operator places a pad or tablet in position on the carriage 62 and allows the carriage to move to the left as viewed in Fig. 10, until a stop pin 84 engages the stop 82 to bring the tablet into proper position for drilling and inserting the fastener. The operator then depresses the pedal 69 to drill a pair of holes in the tablet or pad 11 without causing the operation of the fastener inserter, then shifts the foot slightly to the left, as viewed in Fig. 10, so as to rest on both pedals 69 and 70, and then depresses both pedals to cause the insertion of a fastener 4 into the two holes and to cause the drilling of two holes spaced from the first two holes for the subsequent insertion of another fastener.

For the insertion of the final fastener element of the tablet sheets, the operator may either depress both pedals 69 and 70, causing the rise of the drill head and the insertion of a fastener in the last pair of holes in the tablet (the tablet having passed beyond the position in which it will be in the path of the drills), or the operator may simply depress the inserter pedal 70 causing the insertion of a fastener without any axial movement of the drill head. When the last fastener has been inserted in the tablet, the operator depresses the carriage-return pedal 71, causing the carriage to return to its initial position.

Fig. 19 is a perspective view showing a multiple coil fastener 223 which is designed to be inserted to an extent which will form several coils from each leg of the fastener.

Fig. 20 shows the elongated fastener of Fig. 19 before it is inserted.

I have found that fasteners with a colored coating may be made by providing the wire with a coating of coloring material before the fasteners are formed. The forming of the fasteners does not materially injure the coating. This enables fasteners to be made in various colors to harmonize with the tablet covers, or the like.

While the word "tablet" has been used in describing the apparatus, it is to be understood that this apparatus may be useful in any situa-

tion where it is desired to perforate and bind sheets.

Further modifications will be apparent to those skilled in the art and it is desired, therefore, that the invention be limited only by the scope of the appended claims.

Having thus described my invention, what I claim and desire to secure by Letters Patent is:

1. Apparatus for binding together the edges 10 of juxtaposed sheets in pads comprising means for successively forming spaced perforations in a pad arrangement of sheets adjacent its edge transversely of the planes of the sheets, means for inserting a fastener through a perforation thus formed, simultaneously with the formation of another perforation, a pad support, guide means for guiding said pad support for shifting the pad arrangement laterally when the perforating means are withdrawn from the perforations, and stop means for limiting this lateral movement to position the pad arrangement for a succeeding perforating and inserting operation.

2. Apparatus for binding together the edges 25 of juxtaposed sheets in pads comprising drilling means for successively forming spaced perforations in a pad arrangement of sheets adjacent its edge transversely of the planes of the sheets, means for inserting a fastener through a perforation thus formed, simultaneously with the formation of another perforation, a pad support, guide means for guiding said pad support for shifting the pad arrangement laterally when the perforating means are withdrawn from the perforations, and stop means for limiting this lateral movement to position the pad arrangement for a succeeding perforating and inserting operation.

3. Apparatus for perforating and binding together the edges of sheets in pads by means of 40 individual deformable fasteners, said fastener having originally a substantially straight entering portion to be formed into a loop embracing a portion of the pad between the perforation and the adjacent edge of the pad comprising means for perforating a pad adjacent its edge, and means for thereafter inserting a fastener through a perforation comprising driving means for forcing said straight entering portion to travel endwise and guide means engaged by said originally straight fastener portion in its movement for curling successive portions of the advance end of said straight portion to cause it to enter said perforation and form a loop extending through said perforation and around the adjacent edge of the pad, said perforations being large enough to enable the free entry and passage of the curled moving end of the fastener, and means for supplying individual fasteners one at a time to said inserting means.

4. Apparatus for perforating and binding together the edges of sheets in pads by means of individual deformable fasteners comprising means for forming perforations in a pad adjacent its edge, and means for inserting a fastener through a perforation thus formed, said fastener having originally a substantially straight entering portion to be formed into a loop embracing a portion of the pad between the perforation and the adjacent edge of the pad, said perforating means entering the pad from the same side as that on which the fastener enters the pad, said inserting means comprising driving means for forcing said straight entering portion to travel endwise and guide means engaged by said originally straight fastener portion in its movement

for curling successive portions of the advance end of said straight portion to cause it to enter said perforations and form a loop extending through said perforation and around the adjacent edge of the pad, said perforations being large enough to enable the free end and passage of the curled moving end of the fastener, and means for supplying individual fasteners one at a time to said inserting means.

5. Apparatus for binding together the edges of perforated sheets in pads comprising means for successively forming spaced perforations in a pad adjacent its edge, step feeding means for feeding said pad edgewise, and means for inserting a fastener through a perforation thus formed, simultaneously with the formation of another perforation, said fastener having originally a substantially straight entering portion to be formed into a loop embracing a portion of the pad between the perforation and the adjacent edge of the pad, said inserting means comprising driving means for forcing said straight entering portion to travel endwise and guide means engaged by said originally straight fastener portion in its movement for curling successive portions of the advance end of said straight portion to cause it to enter said perforation and form a loop extending through said perforation and around the adjacent edge of the pad, said perforations being large enough to enable the free entry and passage of the curled moving end of the fastener.

6. Apparatus for perforating and joining together the edges of sheets in pads by means of individual deformable fasteners, said fastener being originally substantially plural-prong shaped and having a plurality of substantially straight parallel spaced entering arm portions to be formed into a plurality of loops embracing a portion of the pad between the perforations and the adjacent edge of the pad, comprising means for perforating the pad adjacent its edge, and means for thereafter inserting a fastener through said perforations comprising driving means for forcing said straight parallel arm portions to travel endwise and guide means engaged by said straight portions in their movement for curling successive portions of the advance ends of said straight arm portions to cause them to enter said perforations and form loops extending through said perforations and around the adjacent edge of the pad, said perforations being large enough to enable the free entry and passage of the curled moving end of the fastener, and means for supplying individual fastener one at a time to said inserting means.

7. Apparatus for perforating and joining together the edges of sheets in pads by means of individual deformed fasteners, said fastener having originally a substantially straight entering portion to be formed into a loop embracing a portion of the pad between the perforations and the adjacent edge of the pad comprising means for perforating the pad adjacent its edge, means for thereafter inserting a fastener through said perforation comprising driving means for forcing said straight portion to travel endwise and guide means engaged by said straight portion in its movement for curling successive portions of the advance end of said straight portion to cause it to enter said perforations and form a loop extending through said perforation and around the adjacent edge of the pad, said perforation being large enough to enable the free entry and passage of the curled moving end of the individual fastener, and means for supplying fasteners

to said driving means from a stack of fasteners, comprising ejector means for removing the fasteners endwise one at a time from the stack, and aligning means for aligning the removed fasteners one at a time with the endwise driving means.

8. Apparatus for perforating and binding together the edges of sheets in pads by means of individual deformable fasteners, said fastener having originally a substantially straight entering portion to be formed into a loop embracing a portion of the pad between the perforation and the adjacent edge of the pad comprising means for perforating a pad adjacent its edge, and means for thereafter inserting a fastener through a perforation comprising reciprocable driving means for forcing said straight entering portion to travel endwise and guide means engaged by said originally straight fastener portion in its movement for curling successive portions of the advance end of said straight portion to cause it to enter said perforation and form a loop extending through said perforation and around the adjacent edge of the pad, said perforations being large enough to enable the free entry and passage of the curled moving end of the fastener.

9. Apparatus for perforating and binding together the edges of sheets in pads by means of individual deformable fasteners comprising means for forming perforations in a pad adjacent its edge, and means for inserting a fastener through a perforation thus formed, said fastener having originally a substantially straight entering portion to be formed into a loop embracing a portion of the pad between the perforations and the adjacent edge of the pad, said perforating means entering the pad from the same side as that on which the fastener enters the pad, said inserting means comprising reciprocable driving means for forcing said straight entering portion to travel endwise and guide means engaged by said originally straight fastener portion in its movement for curling successive portions of the advance end of said straight portion to cause it to enter said perforation and form a loop extending through said perforation and around the adjacent edge of the pad, said perforations being large enough to enable the free entry and passage of the curled moving end of the fastener.

10. Apparatus for perforating and joining together the edges of sheets in pads by means of individual deformable fasteners, said fastener being originally substantially U-shaped and having two substantially straight parallel spaced entering arm portions to be formed into a pair of loops embracing a portion of the pad between the perforations and the adjacent edge of the pad, comprising means for perforating the pad adjacent its edge, and means for thereafter inserting a fastener through said perforations comprising reciprocable driving means for forcing said straight parallel arm portions to travel endwise and guide means engaged by said straight portions in their movement for curling successive portions of the advance ends of said straight arm portions to cause them to enter said perforations and form loops extending through said perforations and around the adjacent edge of the pad, said perforations being large enough to enable the free entry and passage of the curled moving ends of the fastener.

11. Apparatus for binding together the edges of sheets in a pad by means of an individual deformable fastener, said pad comprising sheets

having aligned perforations adjacent their edges, said fastener having originally a substantially straight entering portion to be formed into a loop embracing a portion of the pad between the perforations and the adjacent edge of the pad comprising inserting means for forcing said straight entering portion to travel endwise, guide means engaged by said originally straight fastener portion in its movement for curling successive portions of the advance end of said straight portion to cause it to enter said perforation and form a loop extending through said perforation and around the adjacent edge of the pad, said perforations being large enough to enable the free entry and passage of the curled moving end of the fastener, and means for supplying individual fasteners one at a time to said inserting means.

12. Apparatus for binding together the edges of sheets in a pad by means of an individual deformable fastener, said pad comprising sheets having aligned perforations adjacent their edges, said fastener having originally a substantially straight entering portion to be formed into a loop embracing a portion of the pad between the perforations and the adjacent edge of the pad comprising inserting means for forcing said straight entering portion to travel endwise, guide means engaged by said originally straight fastener portion in its movement for curling successive portions of the advance end of said straight portion to cause it to enter said perforation and form a loop extending through said perforation and around the adjacent edge of the pad, said perforations being large enough to enable the free entry and passage of the curled moving end of the fastener, and means for supplying individual fasteners one at a time to said inserting means.

13. Apparatus for binding together the edges of sheets in a pad by means of an individual deformable fastener, said pad comprising sheets having aligned perforations adjacent their edges, said fastener having originally a substantially

straight entering portion to be formed into a loop embracing a portion of the pad between the perforations and the adjacent edge of the pad comprising inserting means for forcing said straight entering portion to travel endwise, guide means engaged by said originally straight fastener portion in its movement for curling successive portions of the advance end of said straight portion to cause it to enter said perforation and form a loop extending through said perforation and around the adjacent edge of the pad, said perforations being large enough to enable the free entry and passage of the curled moving end of the fastener, and means for supplying individual fasteners one at a time to said inserting means, said guide means comprising a forming element engageable by the outside of the coiled portion of the fastener, and a forming element engageable by the inside of the coiled portion of the fastener and surrounded by said loop, said loop being removable with respect to said inside forming element by lateral movement of the loop with respect to said forming element.

14. Apparatus for binding together the edges of sheets in a pad by means of an individual deformable fastener, said pad comprising sheets having aligned perforations adjacent their edges, said fastener having originally a substantially straight entering portion to be formed into a loop embracing a portion of the pad between the perforations and the adjacent edge of the pad comprising inserting means for forcing said straight entering portion to travel endwise, guide means engaged by said originally straight fastener portion in its movement for curling successive portions of the advance end of said straight portion to cause it to enter said perforation and form a loop extending through said perforation and around the adjacent edge of the pad, said perforations being large enough to enable the free entry and passage of the curled moving end of the fastener, means for supplying individual fasteners one at a time to said inserting means, and means for bending the rearward end of said fastener to form a portion extending substantially tangentially to said loop portion.

GEORGE G. GRINNELL.
